(57) **CLAIM**

The ornamental design for measuring tape blade graphics, as shown and described.

DESCRIPTION

The patent or application file contains a least one drawing executed in color. Copies of this patent or patent application publication with color drawing(s) will be provided by the Office upon request and payment of the necessary fee.

FIG. 1 is a top plan view of portions of a measuring tape with fractional markings and a corresponding numbering scheme illustrating the measuring tape blade graphics; and, FIG. 2 is a bottom plan view of corresponding portions of the measuring tape with fractional markings and corresponding numbering scheme illustrating the measuring tape blade graphics.

Portions of the measuring tape in FIGS. 1 and 2 have been omitted for ease of illustration.

1 Claim, 2 Drawing Sheets
(2 of 2 Drawing Sheet(s) Filed in Color)

FIG. 1.

FIG. 2.
